UNITED STATES PATENT OFFICE.

JOSEPH F. DONAHUE AND MARION G. STALEY, OF SOUTH BEND, INDIANA.

ROOFING.

Application filed July 14, 1921. Serial No. 484,568.

To all whom it may concern:

Be it known that we, JOSEPH F. DONAHUE and MARION G. STALEY, citizens of the United States, residing at South Bend, in 5 the county of St. Joseph and State of Indiana, have invented certain new and useful Improvements in Roofing, of which the following is a specification.

The invention relates to roofing and has 10 for its object to provide a roof formed from a plurality of square flexible or pliable shingles having their edges interlocked in slots of adjacent shingles.

A further object is to provide a roof 15 formed from a plurality of square pliable shingles, said shingles having two of their converging edges adjacent one of their corners provided with aligned slots or cuts for the reception of adjacent shingles on each 20 side when the slotted ends of the shingles are overlapped, said overlapped shingles receiving the adjacent shingles at a right angle to the alignment of the overlapped shingles.

A further object is to provide a roof covering 25 for houses comprising vertically and horizontally aligned square shingles, said shingles being provided adjacent one of their corners with aligned slots for the reception of the edges of adjacent shingles, thereby 30 forming a complete roof.

With the above and other objects in view the invention resides in the combination and arrangement of parts as hereinafter set forth, shown in the drawings, described and 35 claimed, it being understood that changes in the precise embodiment of the invention may be made within the scope of what is claimed without departing from the spirit of the invention.

40 In the drawings:—

Figure 1 is a top plan view of a portion of a roof formed from interengaged shingles.

Figure 2 is a detail perspective view of adjacent shingles showing the interengagement thereof.

Referring to the drawings, the numeral 1 designates a portion of a roof formed from a plurality of rectangular shaped shingles 2, which shingles are preferably square and 50 made from pliable or flexible material. Shingles 2 adjacent one of their corners 3 are provided with relatively narrow slots 4, which slots are disposed at a right angle to a line drawn between the corners 3 and the 55 corners 3^a of the shingles. The slots may be formed by a saw, a U-shaped knife or by

slitting the shingle with a knife. When cut or slit with a knife a slot would be formed when the edges of the shingle are interengaged with each other. When a roof is 60 being covered, the shingles are laid in vertical and horizontal alignment as clearly shown in Figure 2 with their corners 3 downwardly disposed and their corners 3^a upwardly disposed, and adjacent the lower edge 65 of the roof the roof may be finished with square shingles 5, which shingles 5 are not provided with slots 4 for the reason that it gives a better finish and at the same time the corners 5^a will not be weakened in such a 70 manner that they will bend upwardly. When laying a roof, the shingles 5 are placed in horizontal alignment as shown in Figure 1 with their corners 5^a downwardly disposed, and their corners 5^b upwardly disposed. By 75 so arranging the shingles the other diagonally disposed corners 5^c will be in horizontal alignment with each other, and slightly spaced from each other, thereby allowing the similarly disposed shingles 2 in the course 80 above to receive the diverging edges 5^a of the adjacent shingles 5 in the course below, said diverging edges being received in the aligned slots 4 of the shingles 2. When the edges 5^d are disposed in the slots 4, it will be 85 seen that the portions 4^a of the shingles 2 will engage under the sides of the shingles in the course immediately below and will consequently be held in place and at the same time the inner ends 4^b of the slots will engage the 90 diverging edges of adjacent shingles in the course below at points below the corners 5^c of the shingles 5 and 2^a of the shingles 2, thereby holding the shingles against downward movement and maintaining the same 95 in interlocked engagement with each other in such a manner that they are prevented against downward movement and against curling upwardly at their lower ends, which is a great objection with pliable or flexible 100 shingles used at the present time.

It will be seen that one standard form and size of shingle may be used for the entire roof if so desired, thereby allowing the shingles to be easily and cheaply manufactured, and also that the interengaging and interlocking means is extremely simple, thereby allowing the roof to be quickly formed at a minimum cost. By providing relatively narrow slots or cuts, the adjacent shingles 110 when disposed in the cuts are held in such a manner whereby when a workman walks

over the roofing a sharp bend is not formed in the shingles which are disposed in the slots and consequently the material is not fractured.

5 The invention having been set forth what is claimed as new and useful is:—

1. A roof formed from a plurality of rectangular shaped shingles having opposite corners in vertical and horizontal alignment, 10 said shingles having their lower ends provided with horizontally disposed aligned narrow slots, the adjacent shingles having their downwardly converging sides disposed in said slots and held against downward 15 movement by the inner ends of said slots.

2. A roof formed from shingles having corners, said shingles adjacent one of their

corners being provided with aligned slots extending inwardly from their converging edges, the adjacent shingles having their diverging sides disposed in and engaging the inner ends of said aligned slots. 20

3. A roof formed from square shingles, 25 said shingles adjacent one of their corners being provided with slots extending inwardly towards each other from their converging edges, said shingles being formed from pliable material, the diverging edges of adjacent shingles being disposed in said slots and engaging the inner ends of said slots. 30

In testimony whereof we affix our signatures.

JOSEPH F. DONAHUE.
MARION G. STALEY.
